CLAIM

We claim the ornamental design for a electronic device holster, as shown and described.

DESCRIPTION

FIG. 1 is a front perspective view of an electronic device holster;

FIG. 2 is a rear perspective view thereof;

FIG. 3 is a rear elevation view thereof;

FIG. 4 is a front elevation view thereof;

FIG. 5 is a right elevation view thereof;

FIG. 6 is a left elevation view thereof;

FIG. 7 is a top plan view thereof; and,

FIG. 8 is a bottom plan view thereof.
